DESIGN FOR A FLORAL CONTAINER

Roderick M. Koch, Evansville, Ind.

Application September 12, 1936, Serial No. 64,833

Term of patent 7 years

To all whom it may concern:

Be it known that I, Roderick M. Koch, a citizen of the United States, residing at Evansville, Indiana, in the county of Vanderburg and State of Indiana, have invented a new, original, and ornamental Design for a Floral Container, of which the following is a specification, reference being had to the accompanying drawing, forming a part thereof.

Fig. 1 is a perspective view of a floral container, showing my new design.

Fig. 2 is a side elevational view of the same.

Fig. 3 is a top plan view of the same.

I claim:

The ornamental design for a floral container, as shown.
